(57) **CLAIM**

The ornamental design for an applicator for applying a liquid to a surface, substantially as shown and described.

DESCRIPTION

FIG. 1 is a front top perspective view of an applicator for applying a liquid to a surface;

FIG. 2 is a front bottom perspective view of an applicator for applying a liquid to a surface;

FIG. 3 is a front view of an applicator for applying a liquid to a surface;

FIG. 4 is a back view of an applicator for applying a liquid to a surface;

FIG. 5 is a right view of an applicator for applying a liquid to a surface;

FIG. 6 is a left view of an applicator for applying a liquid to a surface;

FIG. 7 is a top view of an applicator for applying a liquid to a surface; and,

FIG. 8 is a bottom view of an applicator for applying a liquid to a surface.

Portions shown in broken lines represent unclaimed portions of the claimed design.
